(57) **CLAIM**

We claim the ornamental design for swing seat covers, as shown and described.

DESCRIPTION

FIG. 1 is a perspective view of the invention;

FIG. 2 is a right side elevational view of the invention, the undisclosed left side being a mirror image thereof;

FIG. 3 is a front elevational view of the invention, the undisclosed rear being a mirror image thereof;

FIG. 4 is a top plan view of the invention; and,

FIG. 5 is a bottom plan view of the invention.

The broken lines disclosed on the drawing figures are showing conventional stitching.
